UNITED STATES PATENT OFFICE.

HENRY A. FINK, OF OAK PARK, ILLINOIS, ASSIGNOR TO CONTINENTAL CAN COMPANY, INC., OF NEW YORK, N. Y., A CORPORATION OF NEW YORK.

MACHINE FOR REFORMING THE FLANGES OF CAN BODIES.

Application filed November 5, 1926. Serial No. 146,443.

The invention relates to new and useful improvements in machines for re-forming the flanges of can bodies.

Containers which are to be closed by double seaming a can end on to the same are provided with a flange by the can maker, and the end is double seamed on to the can by the packer. It is found that in the shipping and handling of the cans, the flanges often become mis-shaped by being bent at certain portions, and these mis-shaped flanges are likely to cause a leak when the end is double seamed on to the can body.

An object of the present invention is to provide a machine for re-forming the flange on can bodies, which machine includes an inner die member on which the can having the flange to be re-formed is supported in inverted position, and also includes half mold die members adapted to be moved into engagement with the can body above the flange, and wherein mechanism is provided for moving the half molds into operative relation to the can body and subsequently moving the inner die member so as to engage the flange between the die members and straighten or re-form the mis-shaping thereof.

A further object of the invention is to provide a machine of the above type wherein the half molds are moved into and out of engagement with the can body, and the inner die member is raised and lowered carrying the flange of the can into engagement with the half mold die members by a rotating shaft and operating cams formed thereon.

These and other objects will in part be obvious and will in part be hereinafter more fully disclosed.

In the drawings which show by way of illustration one embodiment of the invention—

Figure 1 is a view partly in section and partly in side elevation of the machine embodying the improvements;

Fig. 2 is a front view of the machine; Fig. 3 is a sectional view on the line 3—3 of Fig. 1;

Fig. 4 is a view similar to Fig. 3, but showing the parts as moved to position for releasing the can body after the flange is re-formed;

Fig. 5 is a sectional view on the line 5—5 of Fig. 3;

Fig. 6 is a development of the cams which operate the parts in the machine; and

Fig. 7 is an end view of the sleeve con-

taining the cam raceways and eccentric member.

The invention is directed particularly to a flange re-forming machine, and includes an inner die member which is tapered at its upper end so that it may be readily inserted in a can body which has been inverted and placed over this inner die member. The inner die member is approximately of the diameter of the can body and operates, in the first instance, to round up the can body when it has slipped down over this inner member. The inner member terminates at the lower portion in a ledge forming a die, which cooperates with other members in the straightening or re-forming of the flange on the can body. Cooperating with this inner die member are half mold die members, mounted on swinging arms, which are adapted to be brought into engagement with the can body after it is placed on the inner die member. These half molds engage the can body above the flange, and then the inner die member is raised, so that the flange is pressed upon both sides by the inner die member cooperating with the half mold die members. This reforms or straightens any bends or mis-shapings of the flange.

Referring more in detail to the drawings, the improved flange re-forming device consists of a supporting base 1, on which is mounted two spaced standards 2, 2. These standards 2, 2 carry bearings 3, 3 in which the main operating shaft 4 is mounted. In the present embodiment of the invention, this operating shaft 4 is rotated by means of a crank 5. It will be understood, however, that it may be rotated by any suitable means, and may be continuously rotated by power, if desired.

Mounted on each standard 2 is a vertical guide bar 6. Mounted to slide freely on each guide bar 6 is a bracket 7. Disposed between the brackets 7 is a pitman 8. A connecting pin 9 is secured to the brackets 7, 7 by set screws 10, and this connecting pin passes through the pitman. This pitman operates to raise and lower the brackets 7, 7 on the guide bars 6, 6.

Fixed to the brackets 7, 7 is an inner die member 11. This inner die member 11 has a tapered portion 12 and a shoulder 13. These parts are shaped so that when the can body is placed down over this inner die member,

- the tapered upper portion thereof will readily enter the can body and will round up the body. The flange rests on this horizontal shoulder 13, and the parts are further 5 so shaped that if the flange is forced into contact with the horizontal shoulder, it will be properly re-formed or re-shaped so as to be rolled into the double seam when the end is joined thereto.
- 10 Cooperating with the inner die member are two half mold die members 14 and 15. The half mold die member 15 is carried at the upper end of two spaced arms 16, 16. These arms 16, 16 are fixed to a shaft 17 mounted 15 in suitable bearings 18, 18 carried by the supporting base 1. Each arm 16 carries an inwardly projecting boss 19, and passing through the boss is a pin 20, and mounted on the inner end of the pin 20 is a roller 21.
- 20 The other half mold 14 is similarly mounted on arms 16', 16', in turn carried by a shaft 17' mounted in bearings 18' carried by the supporting base 1. These arms are provided 25 with rollers 22, 22. Mounted on the shaft 4 is a cam sleeve 23. This cam sleeve 23 is provided centrally thereof with an eccentric or crank 24. The pitman 8 cooperates with this eccentric member 24, and as the main shaft is rotated, the inner die member will 30 be raised and lowered in a vertical plane sliding on the guide bars 6, 6. At each side, this eccentric member or sleeve is provided with cam raceways 25, 25'. These cam raceways are similarly shaped, but reverse, and the 35 rollers 21 which are diametrically opposed, run in the cam raceway 25, while the rollers 22 run in the cam raceway 25'. As the shaft is rotated, the rollers will swing the arms 16 and 16' so as to move the half mold die members into operative engagement with the can body and away therefrom.
- The operation of my device is as follows. The can with the mis-shaped flange is inverted, and placed on the inner die member 45 which rounds up the can body and supports the can body. The main shaft is then rotated, and as the shaft rotates, it first brings the half mold die members into operative engagement with the can bodies, after which 50 the inner die member is raised, and this causes the flange to be pressed upon by the inner die member and the half mold die members. The throw of the inner die member is sufficient to bring about a complete re-forming 55 or straightening of the flange if it is bent or mis-shaped in any way. The continued rotation of the shaft will lower the inner die member, and move the half mold die members to their outer position, so that the can body 60 can be lifted from the inner die member.
- It is obvious that minor changes in the 65 details of construction and the arrangement of the parts may be made without departing from the spirit of the invention as set forth in the appended claims.

Having thus described the invention, what I claim as new and desire to secure by Letters-Patent, is—

1. A flange re-forming machine for metal cans comprising an inner die member on 70 which the can is supported in inverted position, half mold die members adapted to engage the can body above the flange, a shaft, a sleeve mounted on said shaft, said sleeve having an eccentric member connected to 75

said inner die member so as to raise and lower the same when the shaft is rotated, and said sleeve having cam raceways adapted to move the half molds into operative engagement with the can body and away from the can 80 body, said eccentric member and said raceways being timed to that the inner die member is raised after the half molds are closed about the can body.

2. A flange re-forming machine for metal 85 cans comprising a supporting base, standards carried thereby, guide bars mounted in said standards, brackets slidable on said guide bars, and an inner die member attached to said brackets, means for raising and lowering the inner die member on said guide bars, half mold die members, swinging arms on which said half mold die members are mounted, said half mold die members being disposed so as to move into cooperative 90 relation with the can body above the flange thereon when said can body is inverted and placed on said inner die member.

3. A flange re-forming machine for metal 95 cans bodies comprising a supporting base, 100 standards carried thereby, an actuating shaft mounted on said standards, guide bars mounted on said standards, brackets slidable upon said guide bars, an eccentric member on said shaft, a pitman connecting said eccentric member to said brackets for raising and lowering the same, an inner die member mounted on said brackets on which an inverted can may be supported, and half mold die members movable toward and from the 110 can body for encircling the can body above the flange thereon and for cooperating with said inner die member in re-forming the flange on the can body.

4. A flange re-forming machine for metal 115 cans bodies comprising a supporting base, standards carried thereby, an actuating shaft mounted on said standards, guide bars mounted on said standards, brackets slidable upon said guide bars, an eccentric member 120 on said shaft, a pitman connecting said eccentric member to said brackets for raising and lowering the same, an inner die member mounted on said brackets on which an inverted can may be supported, half mold die members movable toward and from the can body for encircling the can body above the flange thereon and for cooperating with said inner die member in re-forming the flange on the can body, swinging arms for supporting 125 130

said half mold die members, and cams carried by said actuating shaft for oscillating said swinging arms for moving the die members into cooperative relation with the can body and away from the can body for releasing the same.

5. A flange re-forming machine for metal cans comprising an inner die member on which the can is supported in inverted position, half mold die members adapted to engage the can body above the flange, a shaft,

means actuated by said shaft and connected to said inner die member for raising and lowering the same when the shaft is rotated, and means actuated by said shaft for moving the half molds into operative engagement with the can body and away from the can body, said actuating means being timed so that the inner die member is raised after the half molds are closed about the can body. 15 20

In testimony whereof, I affix my signature.
HENRY A. FINK.
